RAILWAY TRUCK

Glenn F. Couch, Rochester, N. Y., assignor to
The Symington-Gould Corporation, Rochester,
N. Y., a corporation of Maryland

Application May 24, 1940, Serial No. 337,101

48 Claims. (Cl. 105—197)

The invention pertains to a railway truck and more particularly to a spring plankless, flexible type thereof.

An object of the invention is to provide a flexible railway truck adapted to adjust itself to and absorb service impulses.

A feature of the invention is to arrange, in a railway truck, a bolster structure, a part of which has a controlled pivotal or horizontal angular movement.

A further feature of the invention is to provide, in a railway truck, a side frame and a resiliently supported bolster structure with means interposed between the side frame and bolster structure for snubbing or retarding the vertical movement of the bolster structure.

An added feature of the invention is to provide a means, in a railway truck, adapted to create frictional forces during a vertical movement of the bolster structure relative to the side frame.

Another feature of the invention is to arrange means, in a railway truck, capable of creating a greater degree of frictional forces when subjected to movements in one direction than in the opposite direction.

A more detailed feature of the invention is to provide, in a railway truck, a two-part bolster structure positioned in a window opening of a side frame, shoes reacting transversely between one part of the bolster structure and the side frame, and resilient means reacting against shoes and the other part of the bolster structure.

The above object and features, as well as numerous others will become apparent from the succeeding description considered together with the accompanying drawings, wherein:

Figure 1 is an elevational view of a railway truck embodying the present invention and shown partially in section to more clearly illustrate the relation of parts.

Figure 2 is a horizontal sectional view taken along the lines 2—2 of Figure 1, looking in the direction of the arrows.

Figure 3 is a cross sectional view taken along the lines 3—3 of Figure 1, looking in the direction of the arrows.

Figure 4 is a cross sectional view taken along the lines 4—4 of Figure 1, looking in the direction of the arrows.

Figure 5 is an elevational view of a railway truck embodying a modification of the present invention and shown partially in vertical section to clarify the illustration.

Figure 6 is a horizontal sectional view taken

along the lines 6—6 of Figure 5, looking in the direction of the arrows.

Figure 7 is a vertical cross sectional view taken along the lines 7—7 of Figure 6, looking in the direction of the arrows.

Referring now in detail to the drawings, and particularly Figures 1 to 4 thereof, wherein like reference characters designate like parts, a railway truck, only a part of which is illustrated, 10 is indicated in a general manner by the numeral 1. The railway truck of the present embodiment is desirably of the spring plankless type and, therefore, is constructed and arranged to lend itself within predetermined limits to impulses

15 imparted thereto during service. Making up transversely spaced, longitudinally disposed load carrying members of the truck is a pair of counterpart side frames 2, only a portion of one being illustrated, since it is well known in the art that 20 two such side frame members form the transverse limits of the truck. Only the single disclosed side frame will be hereinafter described in detail, it being clearly understood that the undisclosed side frame is of the same design, construction or arrangement of parts.

Each side frame comprises a compression member 3 desirably channel- or inverted U-shape in vertical section and having a web 4 with transversely spaced flanges 5 depending from adjacent 30 the lateral limits thereof. A tension member 6, having a central portion spaced a predetermined distance below the compression member, is made up of upper and lower substantially horizontal webs 7 and 8, respectively, joined by side flanges 9 to form an intermediate box-like structure. The upper web is desirably extended laterally beyond the planes of the flanges 9, as at 10, to present an appreciable bearing or supporting area for a group or nest of springs 11, illustrated diagrammatically. The tension member has inclined end portions 12 directed upwardly and outwardly toward the extremities of the side frame where they join or merge with the compression member and related parts (not shown).

40 The upper web 7, intermediate the extended planes of the flanges 9, is provided with oppositely directed convolutions or embossments 13 which commence adjacent the transverse vertical plane of the side frame and are directed upwardly and outwardly toward the extremities of the side frame at an angle different from the inclined end portions 12.

Extending and forming connections between the compression and tension members is a pair of longitudinally spaced counterpart guide

columns 14 which define a bolster or window opening 15 therebetween. The guide columns, desirably channel-shaped in horizontal cross section opening toward or communicating with the window opening throughout a desired extent of their upper portions and of substantially channel-shape in horizontal cross section facing away from the bolster opening throughout their lower portions, each comprise a web 16 having inner transversely spaced flanges 17 extending inwardly of the side frame from adjacent lateral edges thereof. The inner flanges 17 are integral with the compression member flanges and terminate short of the tension member top web 7 for the purpose to be hereinafter explained. The flanges 17 are desirably reinforced adjacent their free edges by outer beadings 18 which merge with the webs adjacent their lower extremities. Extending away from the lower portion of each column web are transversely spaced outer flanges 19 which merge with the inclined portions of the tension members. The outer flanges 19 are also reinforced by beadings 20 which are directed inwardly of the side frame from the free edges of the flanges.

Positioned in the upper extremity of the window opening is a composite bolster structure designated generally by the reference character 21 and preferably comprising an adapter member, spring plate or saddle 22 and a superimposed bolster extremity 23. It will be understood that a bolster or load carrying member extends and forms a connection between spaced side frames with only its extremities interlocked with and occupying a portion of the space defined by the guide columns. The adapter member or saddle bears directly upon the nest of springs 11 so that the bolster structure may be resiliently supported from the side frame. The saddle, of generally U-shape when viewed from the front, particular reference being made to Figure 1 of the drawings, forms a cradle for the accommodation of and support for the associated bolster extremity and accordingly comprises a horizontal elongated member, bed plate or base member 24 of a predetermined extent to adequately blanket the underlying group of springs. Upstanding from and adjacent the opposite edges of the base plate is a pair of longitudinally spaced, substantially vertical, transversely extending legs or arms 25 adapted to embrace the associated bolster extremity therebetween. Each bolster extremity is composed of vertically spaced horizontal upper and lower walls 26 and 27, respectively, joined by longitudinally spaced substantially vertical side walls 28 to form a box-like structure in vertical cross section. The side walls of the bolster extremity are desirably spaced a predetermined distance inwardly of the window opening from the saddle legs so that the bolster extremity may move relatively to the saddle, as will be hereinafter pointed out in detail.

As previously indicated, the present structure is designed so as to lend itself or be responsive, within certain predetermined limits, to service impulses, and accordingly the bolster is arranged and constructed to be capable of a pivoting or angling movement in a horizontal plane relative to the side frame and, in this particular construction, also to the saddles. In this respect, therefore, the side frames are permitted to get out of transverse alignment upon application of longitudinal thrusts to one side of the truck such as would be caused by a leading wheel of a

railway truck passing the contiguous extremities of successive rails or from a delivering rail to a receiving rail. In order to accomplish the above and still present appreciable surface bearing or contacting areas between movable parts, the side walls 28 of each bolster extremity are formed with outwardly facing arcuate, convex or cylindrical surfaces 29 substantially coaxial with respect to one another and with respect to an axis formed by the intersection of a vertical longitudinal plane passing through the side frame intermediate its transverse limits and a vertical transverse plane bisecting the side frame, which will be hereinafter conveniently termed, for the sake of brevity, the vertical axis of the side frame. On the arms of each saddle are correspondingly formed inwardly facing arcuate concave or cylindrical surfaces 30 substantially coaxial with respect to one another and the vertical axis of the associated side frame. The saddle surfaces 30 are desirably spaced a predetermined distance from the associated bolster surfaces so as to permit the bolster to move substantially free in service so far as the side walls and arms are concerned and at the same time present appreciable surfaces adapted to contact substantially throughout their entire extent irrespective of the position of the bolster extremity with respect to the side frame. Since a pivotal bolster movement is provided for, it also becomes necessary to limit this movement for otherwise the truck would derail. The bolster limiting means is characterized by transversely spaced surfaces 31 on each bolster side wall, and in the particular present structure these surfaces form inner faces of stop lugs 32 which are instrumental in limiting a transverse movement of the bolster with respect to the side frame. The surfaces 31 are substantially coradial with the vertical axis of the side frame and are desirably angularly disposed in spaced relation to outwardly facing surfaces 33 formed on the saddle legs. The latter mentioned surfaces are also substantially coradial with respect to the vertical axis of the associated side frame. The angle between the adjacent surfaces 31 and 33 is determinative of the permissible angular movement of the bolster extremity, and as will be noted and observed an angular movement of the bolster 40 in one direction will result in full contact between related surfaces 31 and 33 disposed diagonally of the window opening; that is to say, the associated surfaces on one side of the bolster 45 inwardly of the side frame and on the other side of the bolster outwardly of the side frame will be brought into bearing relation upon an angular movement of the bolster extremity in one direction to thereby form a definite or positive stop to arrest a continued pivotal movement of the bolster extremity. The saddle arms have, opposed from the arcuate and radial surfaces, outwardly facing plane substantially vertical surfaces 25a which are spaced from and adapted to engage the adjacent column flange extremities, and in this manner the saddle is prevented or restricted from shifting longitudinally of the side frame beyond a predetermined amount.

As previously stated, the instant truck is of the 70 spring plankless type and, therefore, is desirably devoid of any connecting means adjacent the lower extremities of the side frames for the purpose of holding them in transverse alignment and spaced relation. In trucks where spring planks 75 are employed to function as a tie and thereby

somewhat rigidify the lower extremity of the truck, the side frames thereof may move longitudinally of the truck out of transverse alignment, and for the specific truck of this type attention is directed to Patent No. 2,132,384, granted October 11, 1938 to Donald S. Barrows. In the patented structure referred to the spring plank bears upon the tension members of the side frames throughout an appreciable area, and as the side frames are urged out of transverse alignment the spring plank angles horizontally to result in frictional forces being created on contacting faces of the spring plank and side frames. It has been found that these frictional forces function as a control, dampening or snubbing means to regulate relative side frame movements. While a spring plank is not employed in the embodiment of the present invention, there is provided, however, an arrangement and association of parts whereby frictional forces are created to control, slacken or retard longitudinal movements of the side frames relative to each other. This arrangement is characterized by a downwardly facing substantially horizontal surface 34 on the bolster extremity which bears upon a correspondingly formed upwardly facing surface 35 on the saddle bed plate. The surfaces 34 and 35 are adapted to move relatively to one another upon a pivotal movement of the bolster extremity to thereby create frictional forces tending to maintain the side frames in transverse alignment. The saddle bed plate is provided with an interlocking means or convolution 36 upstanding therefrom intermediate its transverse edges to extend longitudinally and have its ends inclined, as at 37, forming knee braces, to finally merge with the saddle legs. The convolution forms a bridge or wall connecting the arms and reinforcing them against stresses to which they will be subjected in service. The bottom wall of the bolster is provided with an indentation or recess 38 to accommodate the saddle convolution with sufficient clearance being allowed between the bridge and bolster bottom wall to prevent interference therebetween during bolster extremity movements.

It will be noted that the illustrated bolster structure supporting springs are all of the coil or helical type. In this connection it may be well to state that springs of the same type forming a group and of the same size have a substantially uniform period of vibration. Accordingly, at certain speeds of a railway truck and upon passage over rail joints or other irregularities such as might appear in the tracks or road bed, impulses will be transmitted to the truck which will synchronize with the spring vibrations. This synchronization of external impulses and spring vibrations will cause an amplification of the spring vibrations tending to force the springs solid during a compressive movement thereof and, upon recoil, expand them beyond their normal height. This excessive spring travel will eventually result in damage to the springs themselves as well as to the truck, car superstructure and car lading. On the other hand, if this above referred to excessive spring movement is alternated between the groups beneath each bolster extremity the bolster will then have a rocking motion imparted thereto which may result in derailment of the vehicle.

An arrangement has been incorporated in the embodiment of the present invention to check, retard or disturb the bolster spring vibrations, and as illustrative of an arrangement which may be used, the saddle arms are provided with oppositely directed wedge-shaped extremities 39, integrally formed therewith and projecting into the chan-

nels formed by the upper extremities of the guide columns to terminate short of the column webs 16. The wedges are substantially inverted V-shape in vertical cross section to lighten the saddle member and, therefore, are provided with transversely disposed reinforcing ribs 40. Each wedge presents outer surfaces 41 angularly disposed with respect to one another and facing toward their respective associated guide column inner flanges. Associated with each saddle wedge is a pair of substantially counterpart shoes 42 interposed between each wedge and adjacent guide column flanges. The shoes are provided with inner inclined or tapered surfaces 43 in intimate contact with and adapted to be moved relative to the wedge inclined surfaces 41, and by reason of this surface relationship the shoes are adapted to be moved transversely of the truck toward the guide column inner flanges. So as to protect the guide column flanges against wear there have been provided wear plates 44 which are preferably welded to the inner surfaces of the column flanges and form contact means for the engaging shoes. The shoes, therefore, have outwardly facing substantially vertical surfaces 45 which bear against inboard and outboard inwardly facing surfaces 46 of the plates, and upon any movement of the bolster structure in a vertical direction frictional forces will be created on the contacting surfaces 45 and 46 to thereby prevent, disturb or break up harmonic or synchronous vibrations which may be set up in the bolster structure supporting springs. It will also be noted that the particular shoe and wedge arrangement will prevent the saddle from angling horizontally with respect to the side frame upon the execution of a like action by the bolster extremity. The shoes are each provided with an upstanding shoulder 47 which permits a vertical extension of the surfaces 45 thereof to present an appreciable wear plate contacting area.

So as to maintain the shoes in bearing relation with the saddle wedges and column flange plates the bolster extremity is provided with oppositely directed substantially horizontal arms or abutments 48 formed integrally with the bolster extremity side walls and extending therefrom in vertically spaced relation to the saddle wedges to terminate short of the column webs. The bolster extremity abutments are reinforced against any hinging action which may be imparted thereto in service by means of gussets 49 spaced transversely of the truck and joining the transverse edges of the abutments with the bolster extremity side walls. Reacting between the bolster extremity and each shoe is a coil or helical spring 50 which bears against the overlying abutment and subjacent shoe to resiliently urge the shoes downwardly into wedging engagement with the wedges and column wear plates. The compression of the coil springs 50 is determinative of the amount or degree of friction created on the relatively movable shoe and plate surfaces 45 and 46, respectively. Studs 51 or any other suitable or desirable means are formed integrally with the shoes and abutments to extend into the coil springs 50 and thereby retain them in a predetermined or operable position. The inner flanges of the guide columns are terminated short of the tension member so that the saddle and bolster extremity may be assembled with their related structure as, by referring to Figure 1, it will be observed that the saddle is of a greater length and the bolster extremity, inclusive of the abutments, of a greater width than the clear opening of the upper extremity of the window opening. It, therefore, becomes

necessary, in assembling the illustrated structure, to first insert the bolster extremity into the lower portion of the window opening and thereafter raise it to occupy a position adjacent the upper extremity of the window opening. The coil springs 50 and the shoes are then applied in the order named, followed by the application of the saddle member, and finally the insertion of the nest of springs in bolster supporting position between the side frame tension member and saddle.

It will be noted, by referring particularly to Figure 3 of the drawings, that upon a compressive or recoil movement of the springs of the group 11, the bolster structure, inclusive of the bolster extremity and saddle, will move in unison, and further, that upon a compressive movement of the springs 11, resulting in a downward movement of the bolster structure, the shoes remain substantially fixed relative to the wedges and abutments to create a certain predetermined degree of frictional forces. However, upon a recoil of the bolster supporting springs the shoes are capable of movement away from the bolster extremity abutments and the wedges may increase the pressure of the shoes against the column wear plates, and accordingly a greater degree of frictional forces acting upon the surfaces 45 and 46 is created upon recoil of the bolster supporting springs than upon compression thereof.

By now referring to Figures 5 through 7, the modified species of the invention, whereby there is illustrated a railway truck 1*, also of the spring plankless type, it will be hereinafter noted that the truck now under immediate consideration is substantially a counterpart of the previously described structure with variations in construction and arrangement to be pointed out in detail. The railway truck comprises a pair of side frames 2*, only a portion of one being illustrated. Each side frame comprises a compression member 3* and a vertically spaced tension member 6* integrally connected intermediate their extremities by longitudinally spaced, vertically disposed guide columns 14* which define or form the horizontal limits of a bolster or window opening 15*. Each guide column, being desirably of channel configuration in horizontal cross section, comprises a web 16*, disposed transversely of the side frame, and laterally spaced inner flanges 17* directed toward the window opening from the extremities of the column web. The inner flanges extend from the compression member to a position spaced above the tension member so that the lowermost portion of the window opening will be substantially unrestricted between the column webs. Extending outwardly toward the adjacent extremity of the side frame from each column web is a pair of spaced outer flanges 19* which join the column web to the associated portion of the tension member.

Positioned in the upper extremity of the window opening is a multi-part or composite bolster structure 21* comprising an adapter member or saddle 22* and an overlying bolster extremity 23*. As was pointed out in connection with the previously described structure, the bolster forms a tie or connection between a pair of transversely spaced side frames and also functions as a medium through which a superimposed load is transmitted to the side frames. The adapter member or saddle rests upon a subjacent nest or group of springs 11*, illustrated diagrammatically, which is interposed between the side frame tension member and bolster structure in the window opening to form a resilient support. The saddle 22*, of sub-

stantially U configuration when viewed from the front, forms a cradle in which the associated bolster extremity rests and, as such, comprises a horizontal bed plate or base member 24* extended sufficiently to completely overlie the spring group therebeneath. Upstanding vertically from opposite edges of the base member are transversely extending legs or arms 25* embracing the associated bolster extremity therebetween and forming a means whereby movement of the bolster extremity longitudinally of the side frame beyond a predetermined amount is arrested. The bolster extremity comprises vertically spaced upper and lower walls 26* and 27*, respectively, integrally united by longitudinally spaced, substantially vertical side walls 28*.

As in the previously described structure, the instant bolster is adapted to angle in a horizontal plane relative to the side frames and saddles or pivot about two spaced axes so as to impart to the truck a desired degree of flexibility. Accordingly, the side walls 28* of each bolster extremity are provided with outwardly facing arcuate convex or cylindrical surfaces 29* substantially coaxial with respect to one another and the vertical axis of the associated side frame. Likewise, correspondingly formed surfaces 30* are provided on the saddle arms to be disposed in spaced relation to the bolster extremity arcuate surfaces and are desirably arcuate, concave or cylindrical and also coaxial with respect to one another and the vertical axis of the associated side frame.

Means has been provided in the structure to restrict the pivotal or horizontal angling movement of the bolster and, characteristic of such means, tapering or inclined surfaces 31* form the inner faces of stop or guide lugs 32* outstanding from the bolster extremity side walls in overlapping relation with the saddle arms and a portion of the column flanges. The surfaces 31*, at each bolster extremity, are substantially coradial with respect to one another as well as lie in planes substantially radiating from the vertical axis of the adjacent side frame. Forming engaging surfaces for the bolster extremity radial faces are substantially coradial surfaces 33* facing outwardly of the side frame and positioned on the saddle legs as continuations of the concave surfaces. In like manner, substantially coradial outwardly facing surfaces 52 are provided on the side frame column flanges which desirably lie in the same radial planes as or are in alignment with the saddle radial surfaces 33*. The aligned radial surfaces 52 and 33* are angularly disposed to the bolster extremity surfaces 31*, and the included angle therebetween is determinative of the permissible range of bolster angularity since any deviation of the bolster from the normal illustrated position will result in the engagement of the surfaces 31* by the aligned surfaces 52 and 33* at diagonally opposite corners of the window opening to definitely and positively arrest a continued bolster angular movement. It will be here noted that the saddles and side frames are, in the instant structure, both instrumental in limiting the pivotal movement of the bolster beyond a predetermined degree. The saddle arms have substantially vertical transversely disposed and outwardly facing surfaces 25* normally spaced from and adapted to contact correspondingly disposed or parallel surfaces 53 on the column flanges to limit the longitudinal movement of the saddle relative to the side frame.

Contacting friction surfaces are arranged on the bolster extremity and subjacent saddle so as

to control the horizontal angling movement of the bolster. As exemplary of these surfaces, the saddle bed plate has an upwardly facing, substantially horizontal plane surface 35^a bearing against a correspondingly formed downwardly facing surface 34^a on the bolster extremity bottom wall. Since, as will be hereinafter pointed out, the saddle is locked against any movement relative to the side frame other than a substantially vertical movement, any pivotal movement of the bolster extremity will result in the surfaces 34^a and 35^a sliding relative to one another to generate frictional forces which will control the angular movement of the bolster. The saddle bed plate has a centrally disposed longitudinally extending convolution or embossment 36^a which has its extremities inclined, as at 37^a, to form knee braces and finally merge into the saddle arms. In this manner, the saddle arms are reinforced against any spreading action to which they might be subjected in service. The bottom wall of the bolster is formed with an accommodating recess or indentation 38^a which receives the saddle convolution; sufficient clearance being provided about the convolution to permit a free service movement of the bolster.

In this species of the invention the supporting springs of the bolster structure are also desirably of the same type, preferably coil springs, and so as to disturb harmonic actions thereof, hereinabove discussed, friction means is interposed between the bolster structure and side frame. As exemplary of the preferred type of friction means, there is, outstanding from each saddle arm, a wedge 39^a formed integrally therewith to be interposed between the column flanges and terminating short of the column webs so that, upon a slight permissible longitudinal movement of the saddle relative to the side frame, the wedges will not contact the column webs to build up what might be termed a false capacity. Each web presents outer upwardly and oppositely facing surfaces 41^a angularly disposed to one another and the adjacent column flanges. Since the wedges, as will be hereinafter apparent, prevent the saddle from moving in an angular direction relative to the side frame with its associated bolster extremity, it is desirable to reinforce them, and accordingly the portion of the saddle base plate within the confines of the longitudinal planes of the column flanges is, immediately beneath the saddle arms, offset downwardly, as at 54, and then directed outwardly toward the associated column webs to form ledges or gussets 55 merging with the wedges adjacent their lower extremities.

Related with each saddle wedge is a plurality, preferably a pair, of substantially counterpart shoes 42^a spaced transversely of the side frame to be interposed between each saddle wedge and the restricting column flanges. The shoes each have an inclined surface 43^a in bearing relation with a wedge surface 41^a throughout their entire extent, and by reason of this arrangement the wedges are capable of urging the shoes apart transversely of the side frame to react against the column flanges. Consideration has been given to safeguarding the column flanges against possible wear during service, and with this thought in mind wear plates 44^a have been secured by any desired method to the column 70 flanges and particularly to the inner portions thereof. Frictional contacting surfaces have been arranged on the shoes and column wear plates so that through this means forces are created to disturb the vibrations of the bolster 75

structure supporting springs. In this respect, the shoes have outwardly facing surfaces 45^a which bear against and are adapted to move relative to inwardly facing surfaces 46^a on the wear plates. The shoe surfaces 45^a are desirably cylindrical or convex and the like surfaces on a pair of related or adjacent shoes are substantially coaxial relative to one another. In like manner, the wear plate surfaces 46^a are cylindrical or concave, and the surfaces of a column are substantially coaxial with respect to one another and the related shoe convex surfaces. The substantially common axis of the contacting wear plate and shoe surfaces is desirably vertically disposed and preferably midway between the column flanges as well as their longitudinal limits. By thus disposing the shoe and wear plate surface axes, the wear plates, in a fashion, form cups for the accommodation of the shoes and 20 prevent a displacement of the latter longitudinally of the side frame from their illustrated position. These engaging shoe and wear plate surfaces prevent a creepage of the shoes, and therefore the shoes cannot, at any time, shift 25 toward the adjacent extremity of the side frame to contact the column webs. It will also be noted that by forming the engaging wear plate and shoe surfaces arcuate a slightly greater surface engagement may be formed between the shoes and 30 wear plates.

In order to maintain the shoes in bearing relation with the wedges and column flange plates the bolster extremity has oppositely directed substantially horizontal arms or abutments 48^a forming extended continuations of the bolster top wall. The abutments are reinforced against vertically applied forces by means of centrally disposed gussets 49^a extending transversely of the bolster extremity to join the abutments and the bolster side walls. Reacting between the bolster abutments and shoes are coil or helical springs 50^a which resiliently urge the shoes in a downward direction to maintain the shoe and wedge surfaces 43^a and 41^a, respectively, in intimate contact and result in the shoes being urged transversely or outwardly of the side frame to preserve an intimate relation between the shoe and column plate surfaces 45^a and 46^a. It will be noted that the shoes of the instant structure are hollowed or cup-shaped to form spring retaining means as well as permit the introduction, in the species under immediate consideration, of springs of greater capacity than those employed in the previously described construction. Since the lower extremities of the springs 50^a are arrested from being displaced by reason of the cup-shaped shoes no additional means is here required to prevent an unwarranted shifting of the spring, and it becomes necessary to provide only 60 spuds or dowels 51^a depending from the bolster extremity abutments to the interior of the upper extremities of the springs to complete the means for maintaining the springs in a predetermined position.

As will be clearly understood, various changes and alterations may be made to the illustrated and described structure without departing from within the spirit and scope of the appended claims.

I claim:

1. In a railway truck, a side frame having a bolster opening defined by horizontally spaced U-shaped guide columns facing inwardly of said side frame towards said bolster opening, a vertically movable bolster structure positioned in

- said opening between said guide columns, abutments extending outwardly of said bolster structure toward said guide columns, wedge means in lower vertically spaced relation with said abutments extending outwardly of said bolster structure toward said guide columns, means interposed between said wedge means and guide columns adapted to frictionally engage the latter upon vertical movement of said bolster structure, and springs reacting against said abutments and means.
2. In a railway truck, a side frame having a bolster opening defined by horizontally spaced U-shaped guide columns facing inwardly of said side frame towards said bolster opening, a vertically movable bolster structure positioned in said opening between said guide columns, abutments formed on and extending outwardly of said bolster structure toward said guide columns, wedge means in lower vertically spaced relation with said abutments extending outwardly of said bolster structure toward said guide columns, means interposed between said wedge means and guide columns adapted to frictionally engage the latter upon vertical movement of said bolster structure, and springs reacting against said abutments and means, said springs, means and wedge means being constructed and arranged so that greater frictional forces are created during movement of said bolster structure in one direction than in the opposite direction.
3. In a railway truck, a side frame having a bolster opening defined by horizontally spaced guide columns, a vertically movable bolster structure positioned between said columns and comprising a bolster extremity and a subjacent supporting saddle, oppositely directed arms extending toward said guide columns from said bolster extremity, oppositely directed wedges extending toward said guide columns from said saddle, shoes interposed between said wedges and associated guide columns adapted to frictionally engage the latter upon vertical movement of said bolster structure in either direction, and springs reacting against said arms and shoes for maintaining said shoes in a predetermined position.
4. In a railway truck, a side frame having horizontally spaced guide columns defining a bolster opening, a vertically movable bolster structure positioned in said opening between said guide columns, longitudinally directed abutments formed on said bolster structure, longitudinally extending wedges formed on said bolster structure in vertically spaced relation with said abutments, transversely spaced and transversely movable counterpart shoes interposed between each wedge and associated guide column for frictionally engaging the latter, and springs reacting against said abutments and shoes for urging the latter against said wedges.
5. In a railway truck, a side frame having longitudinally spaced guide columns connecting a compression and a tension member and defining a bolster opening, each guide column having a web, transversely spaced flanges connected to said compression member and directed toward said bolster opening from each web, said flanges terminating short of said tension member, a vertically movable bolster structure positioned in said opening, means formed on said bolster structure and extending toward said webs between said flanges, wedges directed toward said webs from said bolster structure, shoes interposed between said wedges and flanges adapted to frictionally engage the latter upon movement of said
- bolster structure, and springs interposed between said means and shoes for urging the latter into engagement with said wedges.
6. In a railway truck, a side frame having a bolster opening defined by longitudinally spaced guide columns, a bolster structure positioned in said opening and comprising a bolster extremity and a separate saddle adapted to move vertically in unison, supporting springs interposed between said side frame and saddle, shoes interposed between said saddle and guide columns and adapted to frictionally engage said guide columns, springs reacting against said bolster extremity and shoes for urging said shoes in a downward and outward direction against said guide columns, said springs, saddle and shoes being arranged and constructed so that a greater degree of frictional forces is created upon the recoil of said supporting springs than upon compression thereof.
7. In a railway truck, a side frame having a bolster opening defined by spaced guide columns, a bolster structure positioned in said opening and comprising a bolster extremity and a separate saddle adapted to move vertically in unison, means on said bolster extremity extending into said guide columns, means on said saddle extending into said guide columns, said bolster extremity and saddle having plane horizontally disposed surfaces in constant contact, spring means reacting against said bolster extremity and saddle supporting springs between said frame and bolster structure, and means including said spring means interposed between said bolster structure and guide columns for snubbing the action of said supporting springs, said saddle and bolster extremity being arranged and constructed so that said bolster extremity may angle horizontally with respect to said saddle and side frame within predetermined limits and thereby create frictional forces on said plane surfaces.
8. In a railway truck, a side frame having a bolster opening defined by spaced guide columns, a bolster structure positioned in said opening and comprising a bolster extremity and a saddle adapted to move vertically in unison, means on said bolster extremity extending into said guide columns, means on said saddle extending into said guide columns, resilient means reacting against said bolster extremity and saddle, said saddle being held firmly against rotation relative to said side frame, resilient means interposed between said side frame and bolster structure, an upwardly facing substantially horizontal surface on said saddle, a complementary surface on said bolster extremity bearing upon said saddle surface, said bolster extremity being arranged and constructed so as to be adapted to angle horizontally with respect to said side frame and saddle whereby, upon any angular movement of said bolster extremity, frictional forces will be created on said engaging surfaces of said bolster extremity and saddle.
9. In a railway truck, a side frame having longitudinally spaced guide columns connecting a compression and tension member and defining a bolster opening therebetween, each guide column having a web and transversely spaced flanges directed toward said bolster opening from each web, said flanges being connected to said compression member and terminating short of said tension member, a vertically movable bolster structure positioned in said opening, vertically spaced means formed on said bolster structure and positioned between said column flanges, and

means associated with said vertically spaced means for creating frictional forces on said column flanges upon vertical movement of said bolster structure.

10. In a railway truck, a side frame having longitudinally spaced guide columns connecting a compression and tension member and defining a bolster opening therebetween, each guide column having a web and transversely spaced flanges directed toward said bolster opening from each web, said flanges being connected to said compression member and terminating short of said tension member, a vertically movable bolster structure positioned in said opening, vertically spaced means formed on said bolster structure and positioned between said column flanges, and means associated with said vertically spaced means for creating frictional forces on said column flanges upon vertical movement of said bolster structure, said last-named means being arranged and constructed so as to create a greater degree of frictional forces when the bolster moves in one direction than in the opposite direction.

11. In a railway truck, a side frame having longitudinally spaced guide columns connecting a compression and tension member and defining a bolster opening therebetween, each guide column having a web and transversely spaced flanges directed toward said bolster opening from each web, said flanges being connected to said compression member and terminating short of said tension member, a two-part vertically movable bolster structure positioned in said opening and having vertically spaced means positioned within each guide column, resilient means reacting against said vertically spaced means, one part of said bolster structure being arranged and constructed so as to be capable of angling horizontally with respect to the other part thereof, said last-named bolster part reacting against said column flanges to prevent angling thereof, and substantially horizontal bearing surfaces between said bolster parts whereby frictional forces are created thereon upon a relative horizontal angling movement therebetween.

12. In a railway truck, a side frame having longitudinally spaced guide columns connecting a compression and tension member and defining a bolster opening therebetween, each guide column having a web and transversely spaced flanges directed toward said bolster opening from each web, said flanges being connected to said compression member and terminating short of said tension member, a two-part vertically movable bolster structure positioned in said opening, each part of said bolster structure having horizontally directed means extending between the flanges of each guide column, spring means within each guide column reacting vertically against said horizontally directed means, one part of said bolster structure being arranged and constructed so as to be capable of angling horizontally with respect to the other part thereof, said last-named bolster part reacting transversely of said side frame against said column flanges to prevent angling thereof, substantially horizontal bearing surfaces between said bolster parts whereby frictional forces are created thereon upon a relative horizontal angling movement therebetween, and resiliently urged friction creating means between said bolster structure and column flanges.

13. In a railway truck, a side frame having longitudinally spaced guide columns defining a bolster opening therebetween, each guide column

having a web and transversely spaced flanges extending toward said bolster opening, wear plates inwardly of said guide columns secured to said flanges, a two-part bolster structure positioned in said opening and adapted to move vertically in unison, said bolster structure being arranged and constructed so that one part thereof may angle horizontally with respect to the other, abutments formed on one bolster part, wedges formed on the other bolster part, transversely acting shoes interposed between said wedges and wear plates so as to frictionally engage the latter upon a vertical movement of said bolster structure, and spring means reacting against said abutments and shoes for urging the latter against said wedges, one part of said bolster structure frictionally engaging the other part thereof upon a relative horizontal angling movement therebetween.

14. In a saddle for use with a railway truck, a bed plate adapted to completely overlie a nest of springs, spaced arms upstanding from said bed plate adjacent extremities thereof, an upwardly directed convolution adjacent the center of said bed plate joining said arms, and wedges outstanding from said arms; said wedges having inclined surfaces adapted to engage associated shoes.

15. In a saddle for use with a railway truck, a bed plate adapted to completely overlie a nest of springs, spaced arms upstanding from said bed plate adjacent extremities thereof, an upwardly directed convolution adjacent the center of said bed plate joining said arms, and wedges outstanding from and formed integrally with said arms; said wedges being in substantial alignment with said convolution and having inclined surfaces adapted to engage associated means.

16. In a saddle for use with a railway truck, a bed plate adapted to completely overlie a nest of springs, spaced arms upstanding from said bed plate adjacent extremities thereof, an upwardly directed convolution adjacent the center of said bed plate joining said arms, and wedges outstanding from and formed integrally with said arms; said wedges having inclined surfaces facing upwardly and transversely of said truck.

17. In a saddle for use with a railway truck, a base plate adapted to blanket a nest of springs, spaced arms upstanding from said bed plate adjacent extremities thereof and adapted to engage guide columns of a side frame for limiting longitudinal movement of said saddle, a bridge upstanding from said base plate and joining said arms, arcuate coaxial surfaces on said arms facing one another, coradial surfaces on said arms at extremities of said arcuate surfaces, and oppositely directed wedge means outstanding from said arms and formed integrally therewith.

18. In a railway truck, in combination, a side frame having guide columns defining a window opening therebetween, each guide column comprising a web and transversely spaced flanges, vertically disposed inwardly facing cylindrical surfaces on said column flanges, a bolster structure positioned in said window opening and adapted to move vertically relatively to said side frame, friction means between said bolster structure and column flanges, and cylindrical surfaces on said friction means in intimate contact with said column cylindrical surfaces.

19. In a railway truck, in combination, a side frame having guide columns defining a window opening therebetween, each guide column comprising a web and transversely spaced flanges, coradial surfaces on said flanges, a two-piece bolster structure positioned in said window open-

ing, one of said bolster pieces being arranged and constructed to angle horizontally with respect to said other bolster piece, coradial surfaces on said last-named bolster piece in substantial radial alignment with said flange coradial surfaces, coradial surfaces on said first-named bolster piece normally spaced from and adapted to engage said substantially aligned coradial surfaces for limiting angular movement of said first-named bolster piece, and friction means between said bolster structure and column flanges.

20. In a railway truck, in combination, a side frame having guide columns defining a window opening therebetween, each guide column comprising a web and transversely spaced flanges, vertically disposed cylindrical surfaces on said column flanges, coradial surfaces on said flanges, a two-piece bolster structure positioned in said window opening, one of said bolster pieces being arranged and constructed to angle horizontally with respect to said other bolster piece, coradial surfaces on said last-named bolster piece in substantial radial alignment with said flange coradial surfaces, coradial surfaces on said first-named bolster piece normally spaced from and adapted to engage said substantially aligned coradial surfaces for limiting angular movement of said first-named bolster piece, and friction means between said bolster structure and column flanges; said friction means having cylindrical surfaces in intimate contact with said column flange cylindrical surfaces.

21. In a railway truck, in combination, a side frame having inwardly opening guide columns defining a window opening therebetween, a two-piece bolster construction positioned in said window opening, means outstanding from both bolster pieces extending into said guide columns, resilient means reacting against said outstanding means, one of said bolster pieces being held against rotation relative to said side frame by said guide columns, the other of said bolster pieces being rotatable within predetermined limits in an angular direction relative to said side frame and being in surface contact with said first-named bolster piece to create frictional forces upon any angular deviation thereof from normal position, and spring means interposed between said first-named bolster piece and side frame for the support of said bolster construction from said side frame, both of said bolster pieces being adapted to move vertically in unison.

22. In a railway truck, a side frame having a tension member, a compression member, and spaced U-section columns affording with said members a bolster opening, spring means on said tension member, a spring cap on said spring means with lateral portions extending within said U-section columns, a bolster end received within said opening and seated on said spring cap, lateral means on said bolster end accommodated within said U-section columns, and cushioning means interposed between said lateral means and said lateral portions in engagement with legs of said columns for cushioning relative movement between the bolster and the side frame.

23. In a railway truck, a side frame having a tension member, a compression member, and spaced U-section columns affording with said members a bolster opening, spring means on said tension member, a spring cap on said spring means, a bolster end received within said opening and seated on said spring cap, lateral means on said bolster end accommodated within said U-section columns, and friction means confined

within said columns between portions of said spring cap and said lateral means and having frictional engagement with legs of said U-section columns.

5 24. In a railway truck, a side frame having a tension member, a compression member and spaced U-section columns affording with said members a bolster opening, spring means on said tension member, a two-part bolster structure including a spring cap on said spring means and a bolster end received within said opening and seated on said spring cap, lateral means on said bolster end accommodated within said U-section columns, and friction means supported by said spring cap within said columns and engaged by said lateral means, said friction means reacting against legs of said columns for maintaining one part of said bolster structure and side frame in squared relation.

10 25. In a railway truck, a side frame having a tension member, a compression member and spaced U-shaped columns affording with said members a bolster opening, spring means on said tension member, means on said spring means having lateral portions received within said columns, a bolster end received within said bolster opening and seated on said spring means, lateral means on said bolster end accommodated within said U-shaped columns, and cushioning means associated with said lateral portions and exerting pressure against legs of said U-shaped columns upon a relative vertical movement of said bolster end and side frame.

20 26. In a railway truck, a side frame having a tension member, a compression member and spaced U-shaped columns affording with said members a bolster opening, spring means on said tension member, a spring plate having lateral portions extending into said U-shaped columns, a bolster end received within said opening and seated on said spring plate, lateral means on said bolster end accommodated within said U-shaped columns, and means extending between said lateral means and lateral portions and having frictional engagement with legs of said U-shaped column.

30 27. In a railway truck, a side frame having a tension member, a compression member and spaced U-section columns affording with said members a bolster receiving opening, spring means on said tension member, a spring plate on said spring means, a bolster end received within said opening and seated on said spring plate, lateral means on said bolster end accommodated within said U-shaped columns, and friction means extending between said spring plate and said lateral means and having frictional engagement with legs of said columns; the frictional forces being greater upon a recoil action of said spring means than upon a compressive movement thereof.

35 28. In a railway truck, a side frame having a tension member, a compression member and spaced U-shaped columns affording with said members a bolster receiving opening, spring means on said tension member, a two-part bolster structure received within said opening, one piece of said bolster structure bearing upon said spring means, lateral means on one piece of said bolster structure accommodated within said U-shaped column, and friction means reacting against the other part of said bolster structure and engaged by said lateral means; said friction means reacting against legs of said columns for maintainin

one part of said bolster structure and side frame in squared relation.

29. In a railway structure, a side frame having a tension member, a compression member and spaced columns affording with said members a bolster opening, spring means on said tension member, a spring plate on said spring means, a bolster end received within said opening and seated upon said spring plate, and friction means extending between said plate and bolster end; said friction means being so arranged and constructed that frictional forces are exerted transversely of the truck against said columns and the frictional forces created on said friction means and columns being greater during an expansive movement of said spring means than during a compressive movement thereof.

30. In a railway truck, a side frame having a tension member, a compression member and spaced columns connecting said members to define a bolster opening therebetween, spring means on said tension member, a two-part bolster structure supported by said spring means within said bolster opening, and means including friction shoes interposed between said bolster parts in frictional engagement with each column; said friction shoes reacting against said columns to a greater degree upon an expansive movement of said spring means than upon a compressive movement thereof and maintaining at least one of said bolster parts and side frame in squared relation.

31. In a railway car truck, a side frame having spaced columns and an intervening bolster opening, each column having spaced surfaces therein, a bolster resiliently supported in said opening, rigid means associated and vertically movable with the bolster and extending between the spaced surfaces of each column, friction means in frictional engagement with at least one of said spaced surfaces of each column and in wedge engagement with the adjacent rigid means, and resilient means urging said friction means into engagement with said surface and said rigid means.

32. In a railway car truck, a side frame having spaced columns and an intervening bolster opening, a bolster resiliently supported within said opening, and a friction device associated with each of said columns and comprising friction surfaces carried by said columns, wedge elements associated with the bolster and vertically movable therewith, said wedge elements being disposed within said columns, other elements in frictional engagement with said column surfaces and in wedge engagement with said wedge elements, resilient means compressed against one of said elements and spaced from the other thereof, and means for transmitting forces of said resilient means to the last-mentioned of said elements.

33. In a railway car truck, a side frame having spaced columns and an intervening bolster opening, a bolster resiliently supported within said opening, and a friction device associated with each of said columns and comprising inboard and outboard friction surfaces therein, a wedge element associated with the bolster and vertically movable therewith, said element being disposed intermediate said surfaces, friction means in frictional engagement with at least one of said surfaces and in wedge engagement with said element, and resilient means operatively associated with said friction means to urge the same into said engagement.

34. In a railway car truck, a side frame having

5 tension and compression members and spaced columns defining a bolster opening, each of said columns having inboard and outboard walls, friction surfaces on said walls, a bolster extending into said opening, a member associated with said bolster with end portions housed in said columns respectively, each of said end portions forming a follower associated with a friction device in the adjacent column, each of said friction 10 devices comprising a spaced follower and friction shoes between said followers engaging said surfaces.

35. In a railway car truck, a side frame comprising spaced columns and an intervening bolster opening, inboard and outboard friction surfaces on each column, friction elements engaged therewith, a bolster in said opening and resiliently supported from said frame, a member associated with said bolster, and means carried by 15 said member for actuating said elements during relative movement between said bolster and said frame, said means comprising wedge means in complementary wedge engagement with said elements and resilient means operatively associated with said elements for urging the same into engagement with said wedge means and said surfaces.

36. In a railway car truck, a side frame comprising spaced columns and an intervening bolster opening, inboard and outboard friction surfaces on each column, friction elements engaged therewith, a bolster in said opening and resiliently supported from said frame, a member associated with said bolster, means carried by 20 said member for actuating said elements during relative movement between said bolster and said frame, said means comprising wedge means in complementary wedge engagement with said elements and resilient means operatively associated with said elements for urging the same into engagement with said wedge means and said surfaces.

37. In a railway car truck, a side frame comprising spaced columns and an intervening bolster opening, inboard and outboard friction surfaces on each column, friction elements engaged therewith, a bolster in said opening and resiliently supported from said frame, a member associated with said bolster, means carried by 25 said member for actuating said elements during relative movement between said bolster and said frame, said means comprising friction faces on said member engaging the elements associated with each column, said faces tapering toward respective of the friction surfaces on said column, and means urging said elements against said faces and surfaces.

38. In a railway car truck, a side frame comprising spaced columns and an intervening bolster opening, each column comprising spaced walls, a spring group on said frame in said opening, a bolster supported on said group, friction elements adapted to engage said walls, means urging said elements into said engagement, and means for moving said elements against said walls 30 during relative vertical movement between said frame and said bolster, said means consisting of a member associated with the bolster in wedge engagement with the elements, and resilient means operatively associated with said elements to urge the same into said engagement.

39. In a railway car truck, a side frame comprising spaced columns and an intervening bolster opening, a bolster in said opening resiliently supported from said frame, each column comprising spaced walls, friction shoes engaging said

walls, wedge means engaging said shoes, resilient means within said columns and engaged with said shoes for urging said shoes into engagement with said walls, and an interlocking connection between said wedge means and said bolster.

40. In a railway car truck, a side frame comprising spaced columns and an intervening bolster opening, each column having spaced walls, a friction device accommodated between the spaced walls of each column and comprising friction elements engaging respective walls, an actuating member frictionally engaged with said elements and resilient means operative to urge said elements into engagement with said walls and with said member, spring means on said frame in said opening, a bolster element supported on said spring means, and an interlocking connection between said bolster element and said actuating member; the engagement between said actuating member and one of said elements being operative to frictionally resist out-of-square movement between said frame and said bolster element.

41. In an interlocking member for a railway car truck, an elongated member having intermediate its ends interlocking means for an associated bolster, said member having at each end thereof a pair of oppositely disposed wedge surfaces sloping toward opposite sides thereof.

42. In an interlocking member for a railway car truck, an elongated member having intermediate its ends interlocking means for an associated bolster, said member having at each end thereof oppositely disposed wedge surfaces sloping toward opposite sides thereof.

43. In a railway truck, a side frame having a bolster opening defined by horizontally spaced guide columns, a vertically movable bolster structure positioned in said opening between said guide columns, spaced abutment portions formed integrally with the upper portion of said bolster structure and each carrying a plane horizontal surface arranged for movement vertically with said bolster structure, wedge surfaces between said columns and disposed in lower spaced relation to said horizontal surfaces, said wedge surfaces being carried by and arranged to move vertically with said bolster structure, a friction shoe having a vertical friction face coacting with an associated vertical face of an adjacent guide column, a wedge face on each friction shoe in intimate contact with a related wedge surface for urging said friction shoe toward the vertical face of an associated guide column, and spring means acting against said horizontal surfaces and friction shoes for urging the latter downwardly of said bolster structure.

44. In a railway truck, a side frame having a bolster opening defined by horizontally spaced guide columns, a vertically movable bolster structure within said opening, horizontally directed abutments formed integrally with the bolster structure adjacent the upper portion thereof, plane horizontal surfaces carried by said abutments and arranged to move vertically with said bolster structure, wedge surfaces disposed below said plane horizontal surfaces and arranged to move vertically with said bolster structure so that throughout the entire range of vertical movement of said bolster structure the vertical distance between said plane horizontal surfaces and said wedge surfaces will remain constant, said wedge surfaces starting adjacent the lower limits of said bolster structure and terminating intermediate the height thereof, shoe means in-

terposed between said bolster structure and said columns, said shoe means having plane vertical faces in intimate contact with corresponding faces carried by said guide columns and inclined faces in intimate contact with said wedge surfaces, and resilient means acting vertically against said plane horizontal surfaces and said shoe means.

45. In a railway truck, a side frame having a bolster opening defined by horizontally spaced guide columns, a vertically movable bolster structure positioned in said opening between said guide columns, friction means at each side of said bolster structure and being arranged to create a greater degree of frictional forces during an upward movement of said bolster structure than during a downward movement thereof, each of said friction means comprising means formed integrally with an upper portion of said bolster structure and carrying a downwardly facing surface, an inclined surface in lower spaced relation to said downwardly facing surface, said inclined surface starting adjacent the lower limits of said bolster structure and arranged to move vertically therewith so that the vertical distance between the inclined and downwardly facing surfaces will remain substantially constant throughout the entire range of bolster structure vertical movement, a single means carrying an upright face arranged to contact a correspondingly disposed face carried by an associated column and an inclined face in surface bearing relation with said inclined surface, and spring means interposed between said downwardly facing surface and said single means.

46. In a railway truck, a side frame having a bolster opening defined by horizontally spaced guide columns, a vertically movable bolster structure positioned in said opening between said guide columns, friction means at each side of said bolster structure and arranged to create a greater degree of frictional forces during an upward movement of said bolster structure than during a downward movement thereof, each of said friction means comprising means formed integrally with an upper portion of said bolster structure and carrying downwardly facing abutment surfaces, an inclined surface in lower spaced relation to said abutment surface, said inclined surface being arranged to move vertically with said bolster structure so that the vertical distance between the inclined and abutment surfaces will remain substantially constant throughout the entire range of bolster structure vertical movement, a single means carrying an upright face arranged to contact an upright surface carried by an associated column, a face intermediate the height of said single means and being disposed substantially at right angles to said upright face, an inclined face on said single means angularly disposed to said upright face and in intimate contact with said bolster structure inclined surface, and spring means under initial compression and acting against said abutment surface and intermediate face.

47. In a railway truck, a side frame having a bolster opening defined by horizontally spaced guide columns, a vertically movable bolster structure positioned in said opening between said guide columns, friction means at each side of said bolster structure and arranged to create a greater degree of frictional forces during an upward movement of said bolster structure than during a downward movement thereof, each of said friction means comprising means formed integrally with

an upper portion of said bolster structure and carrying a downwardly facing horizontal surface, an inclined surface in lower spaced relation to said horizontal surface, said inclined surface being arranged to move vertically with said bolster structure so that the vertical distance between the inclined and horizontal surfaces will remain constant throughout the entire range of bolster structure vertical movement, a friction shoe having an outer vertical face in intimate contact with a vertical surface on an adjacent column, a horizontal spring seat carried by said shoe and arranged perpendicularly to said outer vertical face, an inclined face on said shoe spaced from said outer vertical face and in intimate contact with said bolster structure inclined surface, and spring means acting vertically and bearing against said horizontal surface and said spring seat.

48. In a railway truck, a side frame having a 20 bolster opening defined by horizontally spaced guide columns, a vertically movable bolster structure positioned in said opening between said columns, friction means at each side of said bolster

5 and arranged to create a greater degree of frictional forces during vertical movement of said bolster in one direction than during vertical movement in the opposite direction thereof, each friction means comprising means formed integrally with an upper portion of said bolster and having a downwardly facing upper spring seat, wedge means having an inclined surface in lower spaced relation to said upper spring seat, said 10 inclined surface being arranged to move vertically with said bolster so that the vertical distance between the inclined surface and upper spring seat will remain constant, a shoe carrying an outer vertical plane face in intimate contact with a vertical plane surface carried by an adjacent column, a lower spring seat carried by said shoe intermediate the height of and perpendicular to said outer vertical surface, an inclined face on said shoe in intimate contact with said wedge means inclined surface, and a coil 15 spring acting vertically and bearing against said upper and lower spring seats.

GLENN F. COUCH.
